UNITED STATES PATENT OFFICE

CHARLES J. ABELES, OF NEW YORK, N. Y.

DESIGN FOR A READING CABINET

Application filed January 25, 1930. Serial No. 34,289. Term of patent 3½ years.

To all whom it may concern:

Be it known that I, CHARLES J. ABELES, a citizen of the United States, and a resident of the city of New York, borough of Queens, county of Queens, and State of New York, have invented a new, original, and ornamental Design for a Reading Cabinet, of which the following is a specification.

Reference is had to the accompanying

drawing, forming part thereof, wherein

The figure is a perspective view of a reading cabinet showing my new design.

I claim:

The ornamental design for a reading cabinet substantially as shown.

CHARLES J. ABELES.
